PORTABLE TOOL

William H. Grafe, Chicago, Ill., assignor to Skil-saw, Inc., Chicago, Ill., a corporation of Delaware

Application December 29, 1945, Serial No. 637,814

6 Claims. (Cl. 30—241)

1

The present invention relates to improvements in portable tools and more particularly to hand held power driven tools of the metal cutting type.

Heretofore various tools have been designed for the purpose of shearing metal sheets or the like into a desired pattern. In a portable hand held power shear the operator holds the shear in one hand and presses it forwardly through the material as it cuts. The cutting action is usually performed with a reciprocating blade operating in combination with a stationary blade to cut a predetermined course through a metal sheet.

Inherent in the action of this type of shear is a deflecting action which forces at least the edge of the material being cut away, out of the plane of the main work piece. Where a narrow strip is being cut off it has a tendency to curl downwardly, around and back up against the work piece, jamming it against further forward movement.

One object of the present invention is to provide a shear that may be progressed through a work piece without jamming.

Another object is to provide means to deflect the material cut sufficiently so that it will not curl against the work piece making it difficult to press the shear further into the work or otherwise interfere with the cutting operation.

Other objects will be apparent to those skilled in the art from an understanding of the following description and the drawings wherein one embodiment of the invention is set forth and explained for purposes of exemplification.

In the drawings:

Fig. 1 is a sectional view of the side of a tool showing the combination of parts making up the present invention.

Fig. 2 is a front view of the tool showing the location of the deflecting means.

Fig. 3 is a bottom plan view of Fig. 1, again showing the location of the deflecting means.

As exemplified herein, the shear may have a gear housing 10 a ram housing 12 and a tubular ram guide column 14 properly attached to the ram housing and supporting a customary supporting or foot member 16 and its lower stationary blade member or die 18.

Through a gear train 20, partly shown, a driven member 22 is rotated in a suitable bearing 24 mounted in the gear housing 10. An eccentric member 26 may be formed integrally with the driven member 22 and extend into the ram chamber 12. A roller member 28 may be mounted over the eccentric and separated therefrom by a bearing member 30.

A ram 32 is usually mounted in the ram chamber 12 and has a sliding fit within the tubular ram guide column 14. It may be held against its rotation by forming a V-shaped channel 34 in its exterior into which extends a wedge-shaped pin 36 through a suitable opening in column 14. The pin may be adjustably mounted for a sliding fit in its channel through the threaded plug 38 moving in a correspondingly threaded portion of the opening.

At its upper end the ram 32 is slotted to form a cross-head 40 to receive the eccentric 26 and its roller to provide a reciprocating motion to the ram upon rotation of the driven member 22.

The tubular column 14 is cut away on its inner portion as at 42 to afford visibility of the cutting parts to an operator and to afford an easy mounting for the cutting blade 44. For this last purpose the reciprocating ram is cut away or set back approximately 180° and recessed as at 46 to receive the cutting blade within the recess and centrally of the main body portion of the ram. The ram is apertured centrally above the recess and threaded interiorly to receive a correspondingly threaded limiting plug 48. This plug is adjusted inwardly or outwardly to fit tightly against the top of blade 44 after the latter has been properly adjusted with respect to its die 18 to prevent upward movement of the blade with respect to the ram. For this purpose it may have a series of openings 49 for receiving a small pin for manipulation. The blade has an elongated slot 50 whereby it may be adjusted with respect to the ram and held in place by a set screw 52 extending through the slot into the ram.

Opposite the cut-away portion 42 the tubular column extends outwardly as at 54 into a flange for supporting the foot member 16 and may be formed integrally therewith or joined thereto through a pin 55 and bolts 56 as shown. This foot extends downwardly at an angle to the column 14 and rearwardly of the same, then around and forwardly to one side and below the blade 44 as best seen in Figs. 1 and 2.

45 A recess 58 is milled into the foot at right angles to the angle of its plane to receive the die member 18. The die may be adjusted vertically and horizontally in its recess through the vertical bolt 60 and the horizontal bolt 62 for proper cutting action with the blade 44. An elongated slot 61 in the foot below the recess permits bolt 60 to move toward or away from the blade 44.

With the structure thus far described, a narrow strip as it is being cut tends to curl downwardly and back upwardly against the work piece

55

and may jam the cutting operation. Applicant therefore uses a deflecting or guide means interposed in the normal path of deflection of the cut-off material and adjacent the cutting means that restricts the amount of deflection of the trimmed off portion causing it to pass off beneath the heel portion 54 and out of the way.

Various means may be used for this purpose. The deflecting means may be of most any desired shape. It is preferably associated with the forwardly extending portion of the foot 16 and extends outwardly therefrom below the cutting surface of the blade and die. It is so positioned with respect to them that as a portion is cut from a work piece it is deflected from the normal or expected curve given it through the cutting action of the blade and die.

As shown, the deflecting means 64 consists of a stamping cut to fit below the die member 18 and to be held in place between the die and the bottom of the recess by the clamping action of bolt 60. For this purpose the deflecting means may be formed with an outwardly extending blade portion 65 and rearwardly extending leg portions 66 and 67 that pass on either side of bolt 60.

The leg members may be made to fit snugly against the sides of recess 58 to prevent turning of the deflector while the die 18 itself clamps the deflector securely in place against the bottom of its recess through bolt 60.

The deflector blade 65 may be formed arcuately or with a curved contact edge 68 as more clearly shown in Fig. 3 which tends to cause the strip being cut-off to be divergently curved away from the cut edge tending to furnish a spreading or wedging action that may speed the cutting action of the shear.

The deflector has been found advantageous in making cuts centrally through a work piece where the tendency to curl and jam is lacking. The cut-away portion however may be severely deflected at the cut edge from the action of the blade and not easily brought back into the plane of the main body of the work piece. The deflector 64 considerably lessens the amount of deflection and saves material in the trimmed-off portion that might otherwise be treated as scrap.

The deflector and its means of attachment herein shown and described is but one structure for accomplishing the desired result.

The invention may be incorporated into various other embodiments and modifications apparent to those skilled in the art without departing from the spirit or scope of the invention.

I claim:

1. In a portable power driven hand tool of the type described having cutting means for shearing material from a work piece and where the material being cut away is normally deflected beyond the plane of the main body of said work piece by the action of said cutting means, the

combination of deflecting means mounted on said tool and extending below said cutting means into the path of the normally deflected material to restrict the amount of deflection of said material.

2. In a portable power driven hand tool of the type described having cutting means for shearing material from a work piece and where the material being cut away is normally deflected beyond the plane of the main body of said work piece by the action of said cutting means, the combination of deflecting means mounted on said tool below said cutting means and extending into the path of the normally deflected material to restrict the amount of deflection of said material.

3. The combination with a hand held portable power tool of the shear type having a stationary die mounted in a recess of a supporting member and a reciprocating blade for cooperation with said die in shearing a work piece, of deflecting means mounted in said recess below said die and extending outwardly from said supporting member to contact material trimmed from said work piece to guide it from its normal path.

4. The combination as defined in claim 3 wherein the die is adjustably held within its recess by a bolt member and said deflecting means has legs positioned on either side of said bolt member, said deflecting means being clamped into position between said die and the bottom of said recess.

5. The combination as defined in claim 3 wherein said deflecting means has an arcuate curve in its outwardly extending portion to guide said material substantially laterally away from the cut edge of said work piece.

6. The combination with a hand held portable power driven tool of the type described having a supporting member with a stationary die member mounted therein, and a movable cutting blade operatively cooperating with said die to cut a strip of material from a work piece and in which said material tends to curl out of the plane of said material from the cutting action, of deflecting means mounted on said supporting member below said die member and extending into the normal path of the curling strip of material to partially restrict the amount of curl of said strip in the same general direction.
